(57) **CLAIM**

(**) Term: **14 Years**

The ornamental design for a portion of a light and motion
detector assembly, as shown and described.

(21) Appl. No.: **29/179,006**

DESCRIPTION

(22) Filed: **Apr. 3, 2003**

FIG. 1 is a perspective view of a portion of a light and motion
detector assembly showing our design shown, with
the broken line showing for illustrative purposes only and
forming no part of the claimed design;

(51) LOC (7) Cl. **26-05**

FIG. 2 is a front elevation view thereof shown in FIG. 1;

(52) U.S. Cl. **D26/51**

FIG. 3 is a back elevation view thereof shown in FIG. 1;

(58) Field of Search D26/51, 61-65;

362/267, 269, 275, 287, 418, 419, 427;

D10/104-121

and,

362/267, 269, 275, 287, 418, 419, 427;

FIG. 4 is a left side elevation view thereof shown in FIG. 1;

D10/104-121

FIG. 5 is a right side elevation view thereof shown in FIG.
